SIDE FRAME FOR INVALID WHEEL CHAIR

James E. Jones, Toledo, Ohio, assignor to Gendron Wheel Company, Perrysburg, Ohio, a corporation of Ohio

Application December 28, 1955, Serial No. 39,506

Term of patent 7 years

(Cl. D15—1)

FIG. 1.

FIG. 3.

FIG. 2.

Figure 1 is a side elevational view of the side frame for invalid wheel chair, showing my new design;

Figure 2 is a top plan view of the arm rest of the side frame for invalid wheel chair;

Figure 3 is a vertical sectional view substantially on the line 3—3 of Figure 1.

I claim:

The ornamental design for a side frame for invalid wheel chair, as shown.
